UNITED STATES PATENT OFFICE.

THOMAS P. ARCHER AND ERNEST E. HEINTZ, OF DETROIT, MICHIGAN, ASSIGNORS TO TERNSTEDT MANUFACTURING COMPANY, OF DETROIT, MICHIGAN, A CORPORATION OF MICHIGAN.

WINDOW REGULATOR.

Application filed December 26, 1924. Serial No. 758,085.

This invention relates to window regulators and has for its object a non-rattling coupling between the lever arm of the regulator and the window bracket.

5 A lever type of window regulator which has a sliding connection with a window channel bracket is old, and common in the art. However, it is rather difficult to fit the roller in the track on the sash channel 10 or fit the button in a slot in the sash bracket so that it is not loose enough to rattle.

The object of the present invention is to provide an auxiliary yieldable bearing member that acts as an anti-rattler.

15 In the drawings:

Fig. 1 is a fragmentary elevation of a coupé fitted with lever type of window regulator.

Fig. 2 is a cross section taken on the line 20 2—2 of Fig. 1.

Fig. 3 is a fragmentary elevation of the end of the lifting arm.

Fig. 4 is a similar elevation taken at a ninety degree point from that of Fig. 3.

25 The lever type of window regulator is very old and usually comprises a lever arm which has a sliding engagement with the lower sash bar, or what is usually called the window channel. We prefer to employ 30 a single strip window channel that forms the sash bar *a* and a track or groove *b* for the roller *c* of the lifting arm *d*. This lifting arm *d* can be raised or lowered by any 35 form of mechanism, but preferably the segment *e* is provided near its fulcrum. This can be actuated by a driving pinion *f*. This is a familiar form of regulator now quite extensively used. However, it is found in actual practice that it is not possible to fit 40 the roller *c* into the groove or track so that it is absolutely free from rattling. In order to obviate this trouble, we rivet to the end of the arm a spring-bearing strip *h*. This is provided with a struck-out lug *i* 45 which projects through the slot *j* in the arm. The end of this bearing strip is pro-

vided with an enlarged head *k* in the form of a ring arranged to fit over the shank or hub *l* of the roller button *c* before that member is riveted to the lifting arm *d*.

50 This forms a very convenient spring-bearing strip, inasmuch as this is angularly disposed in respect to the lifting arm; consequently ordinarily only the outer end of the ring will bear against the sash bar or 55 the window bracket. Hence there is very little rubbing action so as to eliminate friction and lost effort. On the other hand, this is sufficient to hold the parts from drumming or rattling, due to the vibration of 60 the car. Furthermore, this form of yieldable bearing strip is also a very convenient one in assembling the parts together. The form of sash here shown is assembled to the roller by removing the moulding *x* and 65 tipping the sash inwardly. The spring bearing strip may easily yield clear down to the lifting arm stock to permit the parts to be shifted about in this assembling operation.

70

What we claim is:

1. In a window regulator, the combination of a sash bar provided with a track or recess, a lifting arm having a roller running in said track or recess, and a flat spring 75 supported on the end of the arm and between the roller and the lever and arranged to bear against the track.

2. In a window regulator, the combination of a sash bar provided with a track or 80 groove, a lifting arm provided with a roller having a shank and arranged to run in said track or groove, and a yieldable bearing strip secured to the end of the arm and having a ring portion at its end fitting over the shank 85 of the roller to act as an anti-rattling member.

In testimony whereof we have affixed our signatures.

THOMAS P. ARCHER.
ERNEST E. HEINTZ.
